H. E. WAY.
ELECTRIC LIGHT DISPLAY SYSTEM.
APPLICATION FILED APR. 29, 1911.

1,040,475.

Patented Oct. 8, 1912.

UNITED STATES PATENT OFFICE.

HOWARD E. WAY, OF EASTON, PENNSYLVANIA.

ELECTRIC-LIGHT DISPLAY SYSTEM.

1,040,475.

Specification of Letters Patent.

Patented Oct. 8, 1912.

Application filed April 29, 1911. Serial No. 624,097.

To all whom it may concern:

Be it known that I, HOWARD E. WAY, a citizen of the United States, residing in Easton, in the county of Northampton and 5 State of Pennsylvania, have invented certain new and useful Improvements in Electric-Light Display Systems, of which the following is a specification.

My invention relates to display systems 10 commonly employed for advertising purposes in which a display board supports a multiplicity of incandescent electric lamps which are connected by suitable wiring with circuit making and breaking devices in an 15 operating board wherein the arrangement is such that by manipulating appropriate keys the circuits may be closed to any desired lamps or groups of lamps in the display board to bring to view by means of the 20 glowing lamps any desired letter, combination of letters, words or other characters or designs.

According to my invention I provide an 25 operating board of improved construction which is so organized that the lamp circuits may be easily and quickly closed.

In carrying out my invention, I employ 30 a display board similar to those heretofore used, and I connect the lamps of the display board to stationary contacts in the operating board which coöperate with movable contacts for closing the lamp circuits. The 35 movable contacts are provided with heads of magnetic material or material which can be attracted by a permanent magnet or an electromagnet and moved to the necessary extent to close the lamp circuits. I provide a movable contact of this kind for each 40 lamp circuit so that when a contact is moved it will close the lamp circuit to any desired lamp without closing the circuit of any other lamp. For operating the movable contacts I provide either a permanent magnet or an electromagnet, preferably the 45 latter, which is adapted to be held in the hand of the operator and moved over the operating board to select the proper contacts to move them and thus ignite the desired lamps to display on the display board 50 the desired characters or designs. I preferably place over the contacts a plate of glass and move the magnet over the glass plate in such proximity to the movable contacts that they may be operated. Such 55 glass plate enables the operator to see the

development of the design by inspecting the contacts; affords a rest for the hand of the operator while at work, and avoids any danger of the contacts being accidentally moved mechanically. I have also provided 60 means by which after a number of contacts have been moved from normal position independently they may be simultaneously restored to their normal position.

Other features of my invention will be 65 hereinafter more fully explained.

In the accompanying drawings:—Figure 1 is a diagram showing a display board, an operating board and the circuit connections between the two boards. Fig. 2 is a detail 70 view, showing the devices by means of which the contacts, after having been moved from normal position, may be restored thereto simultaneously. Fig. 3 is a diagram, showing the circuit connections between one set 75 of contacts and one of the lamps, the movable contact being shown by full lines in its normal position, and by dotted lines in the position it assumes after having been moved by the electromagnet. Fig. 4 is a 80 similar view, showing the position of the movable contact after it has been moved by the electromagnet to close the circuit through a lamp. Fig. 5 is a perspective 85 view, showing one set of stationary and movable contacts.

The display board A may be of substantially the same construction as those heretofore used in this art and may be of any desired size and carry any desired number 90 of incandescent lamps B. These may be arranged symmetrically as shown or in any other desired way. Each individual lamp may be connected to a common return wire x and to an individual wire y as is also usual in this art. The source of electric energy C may be of any suitable kind and appropriately located. The system as thus far described it will therefore be observed is of 95 the usual kind and my improvements may thus be applied to display boards of usual construction. The operating board D is, however, of novel construction. It may be made in various ways and yet embody my 100 improvements. The preferred construction is shown in the drawings. The stationary contacts E are mounted on a base F of suitable insulating material, there being preferably a pair of contact plates e, e' connected with each lamp B, one of the contacts 110

e being connected with the common return wire *x* and the other contact being connected with an individual wire *y*. The plates *e*, *e'* are out of contact with each other 5 mechanically and are electrically insulated from each other by the base plate *F*.

In connection with each pair of contacts *E* I employ a movable contact *G*, comprising a shank *g* and a head *g'*. The movable 10 contact *G* is pivoted to a supporting bracket *H* by a horizontal pivot pin preferably arranged mid-way between its upper and lower ends and held in such manner that the end *g*² of the shank may enter between 15 the contacts *e*, *e'* and close the circuit thereof. The head *g'* is preferably made sufficiently large and heavy to provide a weight for holding the contact in either its normal position as shown in Fig. 5 to open the circuit 20 or in the position shown in Fig. 4 to close the circuit through the stationary contacts. The contacts *e*, *e'* and the end *g*² of the movable contact are, however, made somewhat yielding so that when the movable 25 contact is in engagement with the stationary contact it will be held in place by slight pressure which, however, is sufficient to keep the circuit closed unless the movable contact is designedly restored to its normal 30 position. The head *g'* of each movable contact is preferably formed with a part *m* which is differently colored from the other part of the head so that when the movable contact is moved to close its circuit the 35 part *m* will face the operator. In this way when a number of contacts have been moved to close certain circuits to produce a design the same design will appear in the operating board and the operator can thus 40 follow the formation of the design as it progresses, knowing that the design produced on the operating board is produced also on the display board.

To operate the movable contacts I may 45 employ a permanent magnet but preferably use an electromagnet. This may be in the form of a rod of suitable size, preferably about the size of an ordinary pencil, surrounded by a coil having circuit wires connected with any suitable source of 50 electricity. This device is indicated at *M* in Fig. 1. By moving the electromagnet over the operating board and bringing it into proximity to certain selected movable contacts, these contacts may be operated to 55 close corresponding circuits and thus cause corresponding lamps to be ignited in the display board and present any desired characters or designs. The contacts are preferably covered by a glass plate *N* placed just 60 above the heads of the movable contacts and the electromagnet *M* may be moved over this glass plate in sufficiently close proximity to the movable contacts to operate 65 them. The operator may rest his hand on

the glass plate without interfering with the contacts and accidental movement of the contacts is thus avoided, it being impossible to manually and practically operate them except by magnetic devices.

I have provided means by which after different contacts have been moved to close a plurality of lamp circuits they may be all restored to normal position simultaneously. A device for this purpose is shown 70 in Fig. 2 and is also indicated in Figs. 3 and 4. It comprises rods *O* resting on the brackets *H* behind the movable contacts and connected at their ends to a bar *P* at the side of the operating board. Normally the 75 rods *O* are arranged in the position shown in Figs. 3 and 4 so as to permit the movable contacts to swing on their pivots without interference; but when it is desired to restore to normal position all the movable contacts 80 which have been moved to close the lamp circuits, the rod *P* may be moved to cause the rods *O* to engage the movable contacts, move them over to normal position and break the circuits which they previously 85 closed and thus extinguish the lamps with which they are connected.

The construction of the operating board is thus very simple, electromagnetic switches involving the use of separate coils for each 90 set of contacts being dispensed with and the contacts are of such simple construction that a very large number of them may be arranged within convenient reach of the operator on a board of comparatively small 95 dimensions, and in this way also the display board may be made of much larger dimensions than heretofore and contain a greater number of electric lamps, all controlled by an operator in charge of an operating board 100 of relatively small dimensions. A skilled operator can close appropriate circuits and produce the desired designs with great rapidity and any designs may be instantly obliterated and new designs brought to 105 view whenever desired.

I claim as my invention:—

1. In an electric lamp display system, the combination with electric circuits and lamps in said circuits of mechanism for 115 controlling said circuits comprising an operating board provided with stationary contacts, movable contacts co-operating with said stationary contacts to close said electric circuits, said movable contacts being 120 provided with armature members, a movable magnet adapted to co-operate with said armatures to cause said movable contacts to close said circuits, and a transparent insulating covering for said contacts interposed between said armatures and said movable magnet.

2. In a device of the class described, the combination of an operating board provided with a series of pairs of open contacts 130

ranged in electrical circuits, a movable switch member for each pair of contacts adapted to close the same, said switch member being provided with a head of magnetic material, indicating means upon each of said switch members to indicate when said switch has been operated to close a circuit, a single magnet adapted to operate any switch, and a transparent non-combustible covering over said switch members and interposed between the same and said magnet.

3. In combination, a plurality of electric circuits, a switch board holding switches adapted to close the respective circuits, each switch including a pivoted member having thereon areas of different aspects, the arrangement of said areas being such that they are respectively visible and invisible when the switch is respectively opened or closed, a transparent covering for said

switches, and means for opening and closing said switches.

4. In an electric display system the combination with a plurality of electric circuits and lamps in said circuits, of an operating board, switches on the operating board one for each circuit and each of which switches includes a pivoted portion provided with areas of different aspects arranged with relation to the opened and closed positions of the switches whereby the design displayed in the lamps is also displayed on the switches, and means for operating the switches.

In testimony whereof, I have hereunto subscribed my name.

HOWARD E. WAY.
